DISPENSING DEVICE

Harold M. Herman, Chicago, Ill.

Application August 21, 1941, Serial No. 407,816

10 Claims. (Cl. 91—49)

This invention relates to dispensing devices, and its general object is to provide a device for dispensing sheet material from a roll, as for example, paper including toilet tissue, as well as fabric material such as gauze or the like, in a dry or wet condition, in that provision is made for treating or applying liquid deodorant, medicament or antiseptic to the sheet material, to moisten the same, as it is being dispensed, or the material can be dispensed in an untreated or dry condition.

A further object is to provide a dispensing device that includes means for cutting the sheet material in any desired length, as it is unwound or removed from the roll, and the material can be removed, treated and accurately cut in an easy and expeditious manner.

Another object is to provide a dispensing device of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side view of one form of my device, partially in section, and with the cutting means in position for use.

Figure 2 is a front view of the device, with parts broken away and in section.

Figure 3 is a fragmentary vertical sectional view taken through a portion of the device, with the parts in normal position.

Figure 4 is a fragmentary vertical sectional view with parts including the cutting means and liquid tank in operative position.

Figure 5 is a fragmentary perspective view of the form of liquid tank shown in Figures 1 to 4 and looking toward one end of said tank.

Figure 6 is a fragmentary detail view illustrating one end portion of the tank.

Figure 7 is a sectional view taken approximately on line 7—7 of Figure 1, looking in the direction of the arrows.

Figure 8 is a detail view illustrating the knob of the feed roller for the sheet material to be dispensed by the device.

Figure 9 is a fragmentary detail view illus-

trating a slightly modified form of liquid tank.

Figure 10 is a fragmentary detail view illustrating a further modified or weighted form of liquid tank together with a stop therefor to limit its movement to operative position.

Figure 11 is a perspective view of still another modified form of liquid tank.

Figure 12 is a perspective view of a modified form of spool for the roll of sheet material.

Figure 13 is a fragmentary side view illustrating a roll of material on the spool of the form of Figure 12, and with the spool mounted in the holding means thereof.

Figure 14 is a fragmentary longitudinal sectional view taken through one end portion of the spool of Figure 12 in mounted position.

Figure 15 is a plan view of the blank from which the spool of Figure 12 is made.

Referring to the drawings in detail, and particularly to Figures 1 to 8, it will be noted that the form of those figures include a relatively narrow upright supporting bracket made from sheet metal or the like to provide a rectangular rear wall 1 having key hole shaped slots 2 adjacent the ends of its upper edge, to receive screws or the like for securing the device in use. However, a coating 3 of adhesive material may be disposed on the rear face of the wall 1 for securing the device to tile or the like, as generally used in bathrooms, or to any other surface which the use of screws or nails would be unsatisfactory. The adhesive material also prevents the surface from becoming marred by screw or nail holes, as will be apparent.

Formed on and extending forwardly from the rear wall 1 throughout the height thereof are parallel side walls 4 in the form of flanges, which are shaped to provide forwardly directed arms 5 at the upper ends thereof, and the arms are slotted vertically as at 6 from their upper ends to provide bearing seats rotatably receiving the ends of a shaft 7 of the spool 8 for a roll A of sheet material, such as toilet tissue as shown. The shaft has spacing collars 9 mounted thereon at the ends of the spool and the collars may be formed on the spool, but in any event the collars bear against the side walls to hold the spool equally spaced therefrom, as best shown in Figure 2.

Formed on the lower ends of the rear and side walls, is a bottom wall 10 that is forwardly curved from the rear wall and has an upturned flange 11 formed on the front end thereof for the bottom wall to provide a trough, for a purpose which will be later apparent. A screw threaded drain

opening is centrally arranged in the trough and is closed by a plug 12.

Secured to the rear wall 1 and extending therefrom at a forward inclination in bridging relation to the side walls 4 is a guide plate 13 for the sheet material, as it is being removed from the roll A, and the guide plate includes a substantially horizontally disposed forward portion 14 that is slightly curved downwardly and extends beyond the front edges of the side walls, as best shown in Figure 1, as well as terminates in a downturned flange 15.

Mounted for rotation in bearing openings in the side walls are the ends of a shaft 16 of a feed roller 17 that is preferably made from soft rubber or the like having a serrated or longitudinally ribbed outer face to set up a frictional engagement with the sheet material, in that the latter is trained between the roller 17 and the front portion 14 of the guide plate, for directing the sheet material along the upper face of the portion 14, as clearly shown in Figure 1, which also illustrates that the feed roller is mounted in close proximity to a portion 18 of the guide plate that follows the curvature of the feed roller, the portion 18 being spaced from the roller a sufficient distance to allow free passage of the sheet material, but so that the latter will be held against the roller, to bring about positive feeding of the material, as will be apparent. One end of the shaft 16 extends a considerable distance outwardly beyond its side wall, and fixed to the extending end is a knob 19 having a diametrically arranged double headed arrow 20 on the outer face thereof, for a purpose which will be later described.

Bridging the side walls is a bearing rod 21 for the cutter bar, the latter including an arcuate sheet like body 22 having its forward portion outwardly flared in curved formation. Formed on the body 22 along its length is a sleeve 23 that is mounted on the rod 21 for rocking movement of the cutter bar, as will be apparent upon inspection of Figures 3 and 4. The forward edge of the body 22 is toothed as at 24, to provide a cutting edge.

Formed on and along the ends of the body 22 for disposal below the same, are cam like flanges 25 that increase in width toward their rear ends, so that the rear portion of the cutter bar is weighted for normally holding the same in a position, with the cutting edge elevated above the free portion 14 of the guide plate 13, to allow free movement of the sheet material between the cutting edge and the plate as clearly shown in Figure 3. The lower edges of the flanges are curved to provide cams 26 and fixed to the feed roller shaft 16 are substantially rectangular cam lugs 27 disposed an equal distance upon diametrically opposite sides of the shaft 16. The cam lugs have rounded ends engageable with the cam edges of the flanges for lowering the cutting edge in clamping engagement with the sheet material, as shown in Figure 4, to bring about cutting the same, when the depending portion of the sheet is raised and drawn across the cutting edge. The operating lugs 27 for the cutter bar are arranged relative to that of the double headed arrow on the knob to indicate the position of the lugs at all times, so that it can be readily determined when the cutter bar is in clamping engagement with the sheet material, to bring about accurate cutting thereof, as will be apparent.

The liquid tank or container of the form of

Figures 1 to 7, includes a hollow cylindrical body 28 having stub shafts 29 formed on the ends thereof and extending therefrom in eccentric relation therewith, and the shafts 29 have reduced outer ends providing trunnions 30 that are removably mounted in bearing slots 30' in the side walls 4 for disposal of the tank below the forward portion 14 of the guide plate, but in close proximity thereto, as best shown in Figures 1, 3 and 4. The tank is likewise disposed in close proximity to the rear wall 1, so that the eccentric mounting of the tank will bring about engagement thereof with the rear wall to limit the rotation of the tank to an operative position for a purpose which will be later described, and as clearly shown in Figure 4. The tank is urged and held to and in its normal position of Figure 3 by a spring that includes an arm 31 fixed at one end to a side wall of the supporting bracket, as shown in Figure 7, and the spring which is formed from a single strand of resilient wire is coiled about the adjacent stub shaft of the tank as at 32 and thence extends into a finger 33 bearing against a filler spout 34 formed on the adjacent end wall of the body of the tank and about an opening therein, for the passage of liquid within the tank.

The cylindrical wall of the body of the tank is provided with rows of perforations or openings 35 throughout the length thereof and for a limited portion of its circumference, as best shown in Figure 5. It will be obvious that the perforations 35 provide outlet means for the contents of the tank, and in order to control the passage of the contents or liquid from the tank, I provide a cover for the perforations, in the form of an arcuate or sleeve like plate 36 of a length coextensive with that of the cylindrical wall of the body 28 and disposed about a portion of said cylindrical wall for circumferential slidable movement thereon to positions for closing any or all of the perforations 35, or to a position to allow passage of the liquid through all of the perforations, as will be apparent. The cover plate is held on the body by tabs 37 extending laterally from the ends of the plate and disposed about the ends of the cylindrical wall for slidable movement thereon, as best shown in Figure 5, which illustrates that the end walls of the body are countersunk to allow the tabs to contact the inner face of the cylindrical wall.

The cover plate is held in adjusted positions relative to the perforations 35, by a spring latch arm 38 that is carried by the cover plate and receivable in any one of a number of notches 39 arranged in the outer end of the cylindrical wall, as likewise best shown in Figure 5.

From the foregoing, it will be obvious that the sheet material can be dispensed in either a dry or wet condition. When it is desired to dispense the material in a dry condition, the perforations are closed by the cover plate 36, and then the feed roller is turned by its knob in an anticlockwise direction until the desired length of material extends beyond the cutting edge 24. The material is then cut in the manner as previously set forth. However, when it is desired to wet or moisten the material, the cover plate is moved to an open position. The user then presses the material against the perforated portion of the tank, as shown in Figure 3, and at the same time rotates the tank in a clockwise direction, as indicated in Figure 4, until the tank engages the rear wall. When the tank is in that position, the perforations are arranged for the passage of the contents

or liquid therethrough onto the material. After the desired length of the material has been moistened, it is then cut in the usual manner.

In the modified form of Figure 9, it will be noted that the stub shafts 40 extend concentrically from the end walls of the tank, and secured to the inner face of the side wall 4 of the supporting bracket, is a stop lug 41 for disposal in the path of the filler spout 34, to limit rotation of the tank to a position, to allow passage of its 10 contents through perforations. Otherwise the form of Figure 9 is identical to that previously described.

In the form of Figure 10, the stub shafts likewise extend concentrically from the end walls 15 of the tank, and a counterbalancing weight 42 is formed on or otherwise secured to the tank to hold and return the same to its normal position, the weight being engaged with the flange 11 when the tank is in that position, and the tank of this form is limited in its movement to operative or material moistening position, by a stop member 43 arranged in the path of the weight, and formed on the rear wall as shown.

In the form of Figure 11, the stub shafts 44 extend eccentrically from the end walls 45 of the tank 46, and as the stub shafts are disposed in proximity to the outer edges of the end walls, it will be obvious that such arrangement will return to and hold the tank 46 in its normal position. In this form, the filler spout 34 is eliminated and I provide one large opening 47 and two or more small openings 48 for the passage of the contents of the tank 46 therefrom, and the large opening is likewise for the purpose of filling the tank.

In Figures 12 to 15, inclusive, I have illustrated a modified form of spool for the roll A, and that form is made from a single blank of sheet metal as shown in Figure 15 and which includes a rectangular body 49 that is rolled upon itself to provide a cylinder 50, as shown in Figure 12. Formed on the ends of the rectangular body 49 are disk members 51 that are bent to close the ends of the cylinder 50, but are spaced therefrom to provide slots 52 for receiving the arms 5 therein when mounting the spool in use, and the disk members 51 are provided with elongated depressions 53 extending inwardly therefrom to provide lugs to be received in the slots 6, as shown in Figure 14. While this form of spool will not rotate and will be fixed with respect to the arms 5, it will be obvious that it is of a diameter relative to the usual inner tube of a roll of material, such as toilet tissue, that the roll will freely rotate on the spool.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. In a device for dispensing sheet material from a roll, supporting means, mounting means for the roll and supported by the first means, a liquid tank mounted in the supporting means for partial rotation and in the path of the material dispensed from the roll, said tank having means for the passage of liquid therefrom, means whereby said tank is normally urged to and held in a position with the passage means uppermost, and said tank being manually movable for the

passage of liquid therefrom onto the material.

2. In a device for dispensing sheet material from a roll, supporting means, mounting means for the roll and supported by the first means, a liquid tank mounted in the supporting means for partial rotation and in the path of the material dispensed from the roll, said tank having means for the passage of liquid therefrom, means whereby said tank is normally urged to and held in a position with the passage means uppermost, means for guiding the material in covering relation with the passage means, and said tank being manually movable for the passage of liquid therefrom onto the material.

3. In a device for dispensing sheet material from a roll, supporting means, mounting means for the roll and supported by the first means, a liquid tank mounted in the supporting means for partial rotation and in the path of the material dispensed from the roll, said tank being of cylindrical formation and having openings in its cylindrical wall for a portion of its circumference, means whereby said tank is urged to and normally held in a position with the openings uppermost, means for guiding the material in covering relation with the openings, said tank being manually movable for the passage of liquid therefrom on the material for wetting the same, and a cover for the openings to control the passage of liquid from the tank or for completely closing said openings.

4. In a device for dispensing sheet material from a roll, supporting means, mounting means for the roll and rotatably supported by the first means, a liquid tank mounted on the supporting means for partial rotation and in the path of the material dispensed from the roll, said tank being of cylindrical formation and having openings in its cylindrical wall for a portion of its circumference, stub shafts included in the mounting means for the tank and extending eccentrically from the ends of said tank whereby the latter is normally urged to and held in a position with the openings uppermost, means for feeding and guiding the material in covering relation with the openings, and said tank being manually movable for the passage of liquid therefrom on the material.

5. In a device for dispensing sheet material from a roll, supporting means, mounting means for the roll and being rotatably supported by the first means, a liquid tank mounted in the supporting means for rotation and in the path of the material dispensed from the roll, said tank being of cylindrical formation and having openings in its cylindrical wall for a portion of its circumference, a weight secured to the cylindrical wall diametrically opposite the openings to normally urge and hold the tank to and in a position with the openings uppermost, means arranged in the path of the weight to limit rotation of the tank, means for guiding the material in covering relation with the openings, and said tank being manually movable for the passage of liquid therefrom onto the material.

6. In a device for dispensing sheet material such as toilet tissue from a roll, supporting means, mounting means for the roll and supported by the first means, a liquid tank mounted in the supporting means for partial rotation and in the path of the material dispensed from the roll, said tank being of cylindrical formation and having openings in its cylindrical wall for a portion of its circumference, means whereby said tank is urged to and normally held in a position

with the openings uppermost, means for feeding and guiding the material in covering relation with the openings, said tank being manually movable for the passage of liquid therefrom onto the material for wetting the same, a cover for the openings to control the passage of liquid from the tank or for completely closing said openings, said cover being in the form of a partial sleeve coextensive with the length of and slidably mounted about the cylindrical wall, end walls for the tank and countersunk relative to the cylindrical wall, tabs formed on said cover and disposed about the ends of the cylindrical wall for holding the cover on the tank, one of the ends of the cylindrical wall having notches therein, and a spring arm fixed to the cover and receivable in any one of the notches for holding the cover against movement.

7. In a device for dispensing sheet material from a roll, supporting means, mounting means for the roll and supported by the first means, a liquid tank mounted in the supporting means for rotation and in the path of the material dispensed from the roll, said tank being of cylindrical formation and having outlet openings in its cylindrical wall for a portion of its circumference, means whereby said tank is normally urged to and held in a position with the openings uppermost, means for guiding and feeding the material in covering relation with the openings, said tank being manually movable for the passage of liquid therefrom onto the material for wetting the same, end walls for the tank, one end wall having an inlet opening therein, a filler spout secured about the inlet opening, and means secured to the supporting means and arranged in the path of the filler spout for limiting movement of the tank to its wetting position.

8. In a device for dispensing sheet material such as toilet tissue from a roll, an upright supporting bracket including a rear wall, side walls formed on the rear wall, mounting means for the roll and removably mounted in the side walls adjacent the upper ends thereof, a cylindrical liquid tank including end walls, stub shafts secured to the end walls and removably mounted for rotation in the side walls adjacent the lower

ends thereof, said tank having rows of outlet openings along the length of the cylindrical wall thereof and for a portion of its circumference, one of said end walls having an inlet opening therein, a filler spout secured about the inlet opening, a spring formed from a resilient strand of wire to provide an arm having one end fixed to a side wall of the bracket, a coiled portion included in the strand and surrounding one of the stub shafts, a finger extending from the coiled portion and engaged with the filler spout for urging and holding the tank with the outlet openings uppermost, means for feeding and guiding the material in covering relation with the openings, said tank being manually movable for the passage of liquid therefrom on the material for wetting the same, a liquid receiving trough included in the bracket to underlie the tank and having a drain opening therein, and a plug closing the drain opening.

9. In a device for dispensing sheet material from a roll, supporting means, mounting means for the roll and supported by the first means, cutting means for the material, means for feeding and guiding the material from the roll to the cutting means, means mounted for disposal in the path of the material after it leaves the cutting means for wetting said material, and means carried by the wetting means whereby the material can be dispensed in a dry condition.

10. In a device for dispensing sheet material from a roll, supporting means, mounting means for the roll and rotatably supported by the first means, cutting means for the material and mounted for rocking movement, means for feeding the material from the roll, means for guiding the material to the cutting means and associated therewith for the cutting means to clamp the material against the guiding means, means carried by the feeding means and engageable with the cutting means for rocking the latter into and out of clamping engagement with the material, means for wetting the material after it leaves the cutting means, and means whereby the material can be dispensed in a dry condition.

HAROLD M. HERMAN.
